United States Patent Office

Des. 210,545

Patented Mar. 19, 1968

210,545

TOBOGGAN

Ray N. Thompson, 4096 West 5010 South,
Kearns, Utah 84118

Filed Feb. 9, 1967, Ser. No. 5,750

Term of patent 14 years

(Cl. D34—15)

FIG. 1.

FIG. 2.

FIG. 3.

FIG. 4.

FIG. 1 is a perspective view of a toboggan showing my new design;

FIG. 2, a top plan view thereof;

FIG. 3, a side elevational view thereof; and

FIG. 4, a rear elevational view.

I claim:

The ornamental design for a toboggan, substantially as shown.
